(57) **CLAIM**

The ornamental design for a scooter, as shown and described.

DESCRIPTION

FIG. 1 is a perspective view of a scooter showing our new design.

FIG. 2 is a front view of the scooter.

FIG. 3 is a back view of the scooter.

FIG. 4 is a left view of the scooter.

FIG. 5 is a right view of the scooter.

FIG. 6 is a top view of the scooter; and,

FIG. 7 is a bottom view of the scooter.

The broken lines in the drawings depict portions of the scooter that form no part of the claimed design.
